UNITED STATES PATENT OFFICE.

HARVEY S. STONER AND BURTON STONER, OF MASSILLON, OHIO.

ACETYLENE-GAS GENERATOR.

No. 880,698.

Specification of Letters Patent.

Patented March 3, 1908.

Application filed June 7, 1907. Serial No. 377,715.

To all whom it may concern:

Be it known that we, HARVEY S. STONER and BURTON STONER, citizens of the United States of America, and residents of Massillon, county of Stark, and State of Ohio, have invented certain new and useful Improvements in Acetylene-Gas Generators, of which the following is a specification:

This invention relates to new and useful improvements in acetylene-gas generators, and more particularly to what may be termed a "single-tank" generator, and the invention is directed to the structural improvement of acetylene generators, the purpose being to simplify and cheapen such mechanism or apparatus and to render it compact in form.

Further objects are to provide an acetylene-gas generator which occupies but little space, which embodies but few parts, which is particularly adapted for domestic lighting, and wherein the feeding of the carbid is automatically controlled for generating gas only as fast as needed, and wherein a substantially uniform volume of gas is maintained, resulting in the provision of a light of an unusually steady character.

The novelty of the invention resides in certain improvements the exact nature of which will hereinafter appear, reference being had to the accompanying drawing, forming a part of this specification, in which—

Figure 1 is a vertical section of the invention; Fig. 2 is an enlarged detail view, partly in broken section, of the carbid-feeder; and—Fig. 3 is a section on the line 3—3, Fig. 2.

Referring to said drawing, in which like designating characters distinguish like parts of structure throughout the several views—1 indicates a gasometer tank, and 2 the vertically movable bell of the gasometer, while 3 indicates the generator tank, which is seated within the gasometer tank 1, as shown, the diameter of the latter being considerably greater than that of said generator tank.

The upper end of the generator tank 3 is open, and mounted over said open upper end is a carbid-holder 4, supporting legs 5 attached to said carbid-holder being mounted in appropriate sockets 6 provided about the top of said generator tank. Said carbid-holder is provided with a hopper-shaped lower end 7 which terminates in a laterally-directed discharge-mouth 8. Fixed about said mouth 8 is a collar 9 which serves as a bearing for the open side of a rotatable car-

bid-feeder 10, the opposite side of which has fixed thereto the end of a short shaft 11 which is journaled in the lower end of a depending support 12 carried by said carbid-holder. Said carbid-feeder 10, which normally stands in a substantially horizontal or non-discharging position, is of tapered horn-like formation and is adapted, when slightly rotated forward, to discharge a portion of the carbid contained therein from its mouth 13 into the generator tank 3.

Rigidly mounted intermediate its ends upon the outer end of the shaft 11 is a lever 14 the movements of which effect the movements of the carbid-feeder 10. Pivottally connected to the front end of said lever is the lower end of an upright rod 15 which is guided in its movements by a suitable guide 16 carried by the upper end of said carbid-holder and has its upper end elevated an appropriate distance above the top of the carbid-holder. A balance weight 17 carried by the rear end of the lever 14 serves to normally maintain the said lever and, consequently, the carbid-feeder in their normal horizontal positions.

A pivoted cover 18, or a cover of any other appropriate form, is provided as a closure for an opening 19 in the top of the carbid-holder 4 through which said carbid-holder is supplied with carbid. In the top of the gasometer bell 2 directly over the opening 19 is an opening 20 through which access is had to the carbid-holder, and a suitable gas-tight closure 21 is provided therefor.

The gasometer tank 1 is filled with water to a level slightly below the top of the generator tank 3, and the latter is filled with water to an appropriate depth, which, however, must not be such that contact will be made therewith when the carbid-feeder is tipped. Then, having loaded the carbid-holder with carbid, the apparatus is in readiness for operation. A quantity of said carbid being deposited in the generator tank 1, acetylene gas is immediately generated which at once operates to elevate the bell 2, which, as is well understood, is vertically movable with respect to the tank 1 with the fluctuations in the gas supply. The service pipe 22 has its entrance end in the gas zone of the gasometer, as shown, said pipe standing vertical between the tanks 1 and 3. As the generated gas is being exhausted, the bell 2 gradually settles within the tank 1, and, in its descent, the top thereof contacts

with the upper end of the upright rod 15 and gradually forces the latter downward. This, through the lever 14 and shaft 11, operates to partially rotate the carbid-feeder 10, causing it to incline downward and to discharge its contents, or a part thereof, into the tank. 3. The resultant generation of gas produces an immediate elevation of said bell, permitting of the immediate return of the feeder 10 and its correlated parts to their normal positions, such return being effected through the medium of the counter-weight 17.

The generation and supply of acetylene gas by means of this apparatus is made up of 15 a succession of repetitions of the foregoing operation, and, as is obvious, is purely automatic.

As a means of eliminating any possibility of the bell 2 being elevated to a dangerous 20 height with respect to the tank 1, a tube 23 is suspended vertically from the top of the bell between the walls of the tanks 1 and 3 with its lower end submerged in the water of said tank 1 and approaching the lower end of the 25 bell 1; and within said tube, to a point above the level of the water in the tank 1, extends a vertical escape pipe 24 which leads to the atmosphere. As is apparent, when the bell is elevated to a point where the lower end of 30 said tube clears the water, the gas rushes outward through said escape pipe, thus immediately reducing the volume of gas in the gasometer and producing a resultant lowering of said bell.

35 The gasometer tank 1 is filled through a water-bowl 25 provided upon the side thereof, while the generator tank 3 is filled from the top before the carbid-holder is mounted thereon.

40 To remove the various parts for cleaning or other purposes, the bell 2 is first lifted from the tank 1, then the carbid holder 4 is lifted from its place on the generator tank 3, and finally said generator tank is lifted out. 45 Drain cocks 26 and 27 may be employed in the tanks, or may be dispensed with, as desired.

It will be noted that while the construction herein set forth is primarily designed for 50 generators of small capacity, such as are employed for domestic lighting, it is also readily applicable to lighting upon a more extensive scale.

Having thus described our invention, what 55 we claim as new, and desire to secure by Letters Patent, is—

1. The combination with a gasometer, of a generator and a carbid-holder both mounted within said gasometer, a feed-device carried by said carbid-holder, said device comprising a rotatable feeder in open communication with the discharge-end of said holder, a shaft rotatable with said feeder, a lever fixed to said shaft, and an upright vertically movable 65 rod connected to said lever and adapted to be

controlled in its movements by fluctuations in the volume of gas contained in said gasometer.

2. The combination with a gasometer, of a generator and a carbid-holder both mounted 70 within said gasometer, a feed-device carried by said carbid-holder, said device comprising a rotatable feeder in open communication with the discharge-end of said holder and rotatable about said discharge-end, said feeder 75 being of tapered horn-like formation and normally standing in a non-discharging position, a lever in fixed relation to said feeder, a vertically movable rod connected with said lever and adapted to be depressed by the 80 movable member of said gasometer as it descends for actuating said lever to rotate said feeder to discharging position, and means for returning the moved parts to their normal positions with the ascent of said movable 85 member.

3. The combination with a gasometer, of a generator tank mounted within said gasometer, a carbid-holder mounted over said generator tank, said holder having a laterally-directed discharge-end, a carbid-feeder of horn-like formation in open communication with and rotatable about said discharge-end, a shaft fixed to one side of said feeder, a lever fixed intermediate its ends on 90 said shaft, means connected to one end of said lever whereby the downward movement of the movable bell of said gasometer between predetermined points is communicated to said lever whereby the partial rotation of 100 said feeder is effected, and means for returning said lever to its normal position with the upward movement of said bell.

4. The combination with a gasometer, of a generator tank located within said gasometer, a carbid-holder mounted over said generator tank, said holder having a laterally-directed discharge-end, a carbid-feeder rotatable about and in open communication with said discharge-end, a support depending 105 from said carbid-holder, a shaft fixed to said feeder and journaled in said support, a lever mounted upon the end of said shaft, a rod attached to said lever and adapted to be contacted by the movable member of said gasometer at a predetermined point in the downward movement of the latter and to be forced downward thereby to effect the operation of said lever and the resultant tipping of said feeder, and means for effecting the return of 110 the downwardly-moved parts with the upward movement of said member.

In testimony whereof we affix our signatures in presence of two witnesses.
